(57) **CLAIM**

The ornamental design for a shower caddy, as shown and described.

DESCRIPTION

FIG. 1 is a perspective view of the shower caddy according to the invention;

FIG. 2 is a top view of the shower caddy as shown in FIG. 1;

FIG. 3 is a front view of the shower caddy as shown in FIG. 1;

FIG. 4 is a side view of the shower caddy as shown in FIG. 1;

FIG. 5 is a rear view of the shower caddy as shown in FIG. 1;

FIG. 6 is a side view of the shower caddy as shown in FIG. 1, shown from the opposite side as that shown in FIG. 4; and, FIG. 7 is a bottom view of the shower caddy as shown in FIG. 1.

The broken-line disclosure in the views is for illustrative purposes only and forms no part of the claimed design.
